UNITED STATES PATENT OFFICE.

LOESER KALINA, OF BROOKLYN, NEW YORK.

TELEPHONE-RECEIVER HOLDER.

Application filed May 17, 1923. Serial No. 639,702.

To all whom it may concern:

Be it known that I, LOESER KALINA, a citizen of the United States, and a resident of the city of New York, borough of Brooklyn, in the county of Kings and State of New York, have invented a new and Improved Telephone-Receiver Holder, of which the following is a full, clear, and exact description.

10 The present invention relates to new and useful improvements in telephone attachments, and it pertains more particularly to a telephone receiver holder.

It is one of the objects of the invention to 15 provide means for supporting a telephone receiver in order that both hands of a person speaking on the telephone may be free for the purpose of writing memoranda and the like.

20 It is a further object of the invention to construct a device of this character in such a manner that it is adaptable to the conventional type of telephone stands.

It is a further object of the invention to 25 construct a device of this character in such a manner that the same may be folded upwardly into parallelism with the telephone stand and be out of the way when not in use.

It is a further object of the invention to 30 construct the device in such a manner that the receiver-holding member is adjustable in both a vertical and a horizontal plane.

It is a still further object of the invention to 35 construct the device in such a manner that the telephone receiver may be positioned on either side of the telephone stand thereby facilitating use of the device with either ear.

With the above and other objects in view, 40 reference is had to the accompanying drawings, in which—

Figure 1 is a perspective view of a telephone stand equipped with a receiver-holder constructed in accordance with the present 45 invention;

Fig. 2 is a detail sectional view taken on the line 2—2 of Fig. 1, showing the manner in which the device is attached to the telephone stand;

50 Fig. 3 is a detail sectional view of the receiver-holding element, showing the manner in which it is adjustably secured in position;

Fig. 4 is a plan view of the attachment of 55 the receiver-holding element;

Fig. 5 is a detail view showing the tele-

phone receiver holder folded to position in parallelism with the telephone stand.

Referring more particularly to the drawings, the reference numeral 5 designates a 60 conventional form of telephone stand.

In carrying out the invention a bushing 6 of suitable material is employed, such bushing being preferably formed in two pieces. This bushing is adapted to embrace 65 the standard of the telephone stand and be secured thereon by means of a two-part band 7. The parts of this band are secured together at one side by means of a bolt 8, and at the other side by means of a bolt 9, the bolt 9 70 having a wing nut 10, by means of which the two-part band is caused to grip the two-part bushing 6 and secure the same to the standard of the telephone stand. Connected to the bolt 8 are laterally extending members 11, provided with upwardly-bent ears 12 on the ends thereof, the purpose of which ears will be hereinafter described.

The reference numeral 13 designates a two-part band, the parts of which are secured together at one side by means of a bolt 14 having a wing nut 15, and at the other side by means of a bolt 16 having a wing nut 17. Pivots mounted on this bolt 16, is an arm 18, and embracing the lower end of such arm is a U-shaped clip 19, said clip limiting the downward movement of the arm 18. Pivots connected to the outer end of the arm 18, as by means of a bolt 20, is a right-angular member 21, and embracing the upper end of the arm 18 and the upper end of the edge of the right-angular member 21, is a U-shaped clip 22, which serves to limit the upward movement of the right-angular member 21. This clip, 95 however, in no way limits the downward movement of the member 21 since the inner end thereof is curved, as designated by the reference numeral 23, which permits of its passing beneath the U-shaped clip without 100 binding action.

Rigidly secured, as at 24, to the right-angular member 21, is a vertical standard 25, and the lower end of this vertical standard is provided with a right-angular extension 26 forming a foot. The upper end of the standard 25 is right-angularly disposed, as at 27, and pivotally mounted on said right-angularly disposed end, by means of a bolt, or the like, 28, is a member 29 105 having a vertical extension 30. A U-shaped clip embraces the right-angular extension 110

27 of the member 25 and the end of the member 29, such clip being designated by the reference character 31. The reference numeral 32 designates two spring arms 5 adapted to embrace a telephone receiver 33'. The two spring arms 32 are pivotally secured to the vertical extension 30 of the member 29, by means of a bolt 33, and embracing the ends of the spring members 32 10 and the right-angular extension 30, is a U-shaped clip 34.

The band 13 heretofore mentioned is adapted for pivotal movement about the stand, thus providing means for pivotally 15 mounting the arm 18 in such a manner that it may swing about the stand 5. The arm 18 in swinging about the stand, however, is limited by means of the lugs 12 of the members 11 since it is engaged by these lugs in 20 its swinging movement. The members 11, however, are preferably formed of resilient metal and may be bent downwardly to a point where the arm can swing therewith if occasion so requires.

25 The device is shown in Fig. 1 in the position in which it is employed for supporting a telephone receiver, and with the receiver positioned in this manner both hands of the operator are free for other us.

30 By constructing the receiver holder as above outlined, the same is mounted for adjustment in a horizontal plane about the bolt 28, and for adjustment in a vertical plane by the bolt 33, and by this construction proper adjustment of the receiver may 35 be had. In addition, the telephone receiver is adjustable about the telephone stand in order that it may be positioned on either side of the telephone stand for use in connection with either ear of a listener.

40 When the device is not in use, the receiver is removed from the resilient members 32 and supported upon the hook of the telephone stand in the ordinary manner. 45 When this is done it is only necessary to move the arm 18 upwardly, the bolt 16 serving as the pivot therefor. Simultaneously with the arm 18 swinging about the pivot 16, the vertical standard 25 will swing

about the bolt 20 as its pivotal point, and the arm 18 and the vertical standard 25 will move into parallelism with each other and with the standard of the telephone stand and the receiver will be positioned where the same will not be in the way and will 55 not interfere with the usual operation of a telephone stand.

While in the present instance the device is illustrated as having two bands 7 and 13, it is obvious that the band 7 may be eliminated and that the arm 18 may be pivoted in a horizontal plane to the band 13, and such band be clamped tightly about the telephone stand.

What is claimed is:

1. In combination with a telephone stand, a band adapted to be rigidly secured thereto, a second band pivotally mounted on said rigidly secured band, an arm carried by said second-mentioned band and adapted to have 70 pivotal movement about the telephone stand, and means carried by said rigidly secured band for limiting the pivotal movement of said arm.

2. A telephone receiver support comprising a band adapted for rigid attachment to a telephone stand, a second band adapted for pivotal attachment to said telephone stand, said first-mentioned band forming a support for the second-mentioned band, and means for limiting the pivotal movement of said pivoted band, said limiting means being carried by said rigidly secured band.

3. A device of the character described comprising an arm adapted to be secured to a telephone stand and have horizontal pivotal movement thereabout whereby the receiver may be moved to either the right- or left-hand side of the stand, and means rigidly carried by said stand for limiting the horizontal movement of said arm and thereby determining the right or left position of said arm, said means comprising a pair of oppositely disposed rigid arms carried by the telephone stand and an upstanding resilient lug formed on the free end of each of said arms.

LOESER KALINA.
